ROTARY PUMP

Charles Smith, Albert E. Prohaska and Albert L. Wilson, Denver, Colo., assignors of one-fourth to O. B. Schmidt, Denver, Colo.

Application August 10, 1933, Serial No. 684,520

4 Claims. (Cl. 103—136)

This invention relates to a rotary pump. Rotary pumps of the pressure type have not been commercially successful owing to the fact that when operating against heavy pressures or upon fluids containing abrasive substances, the pumps are subjected to rapid wear and deterioration which soon renders them useless or inefficient. The principal object of this invention is to provide a rotary pump construction in which this excessive wear will be eliminated or greatly reduced, and to provide a pump which can operate against high pressures indefinitely.

In the usual rotary pump, the pump vanes are pressed against the interior of the housing by centrifugal force, and, in some instances, by springs. This excessive pressure increases with the speed that the pump is operating causing a high coefficient of friction and a rapid wearing away of the vanes and walls. Another object of this invention is to provide a construction by means of which the vanes can be prevented from coming in actual contact with the housing walls so that wear at this point may be entirely eliminated.

Another disadvantage of the usual rotary pumps resides in the fact that the fluid being pumped leaks into the bearing for the pump shaft so as to carry foreign materials therein or create corrosion thereon. A further object of this invention is to provide a construction in which there can be no leakage of the fluid being pumped into the bearing area.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a vertical cross section through a rotary pump in which the features of this invention have been embodied. The section in this view is taken on the line 1—1, Fig. 2.

Fig. 2 is a longitudinal section through the pump of Fig. 1, taken on the line 2—2, Fig. 1.

Fig. 3 is a detail section through a portion of the pump rotor and vane, taken on the line 3—3, Fig. 1.

The improved pump consists of a cylindrical pump chamber 10. Each face of the pump chamber 10 is closed by means of a circular face plate 11. A shaft 12 passes completely through both face plates 11 and through the pump chamber 10. Packing glands 13 are provided to prevent leakage about the shaft 12. The shaft 12 is supported in a pair of out-board

journals 14 preferably provided with suitable ball bearings 15. The journals 14 are supported from the face plates 11 upon suitable strengthening ribs 16 cast or otherwise formed thereon. It will be noted that the shaft 12 passes through the pump chamber 10 eccentrically, preferably, but not necessarily, above the center line of the chamber.

A circular rotor 17 is keyed to the shaft 12 within the chamber 10. This rotor is of a diameter to bring its periphery closely adjacent to the inner wall of the chamber 10 on the side of the greatest eccentricity.

The rotor 17 is provided with a series of lateral, radially extending, slots 18 in each of which a vane 19 is arranged to reciprocate. The vanes 19 have a thickness substantially equal to the width of the slots 18 and are of a width to substantially fill the space between the heads 11. The friction between the vanes 20 and the rotor is relieved by means of roller bearings 20 which are positioned at each side of each vane within the rotor 17.

Each vane is longitudinally bifurcated to form a slide for a sealing block 21, each of which carries a rotatable sealing bar 22. The blocks 21 may be moved outwardly or inwardly to vary the space between the sealing bars 22 and the inner surface of the pump chamber 10 by means of a pair of wedge blocks 23. The wedge blocks 23 are mounted in pairs in each vane upon threaded rods 24. The threads at the opposite extremities of the rods 24 are opposite hand, so that as the rod is rotated, it will act either to draw the wedge blocks toward each other or push them away from each other. It will be noted that the wedge blocks act against inclined surfaces 25 on the bottoms of the sealing blocks 24, and that they are dovetailed as shown at 26 to fit corresponding dovetailed grooves in both the rotor and the sealing blocks.

A full floating wheel shaft 27 extends longitudinally through each of the vanes 19 and is preferably journalled therein on roller bearings 28. A bearing wheel 29 is secured on each extremity of each wheel shaft 27. The bearing wheels 29 travel in a circular indented track groove 30 in each face plate 11. The tracks 30 are concentric with the axis of the pump chamber 10 and the width of the track grooves 30 is substantially equal to the diameters of the wheels 29.

The pump chamber 10 is provided with fluid nipples 31 and 32 and preferably with a supporting base 34. The face plate may be detachably clamped to the pump chamber 10 by means of suitable bolts 33.

It is desired to call attention to the fact that either of the nipples 31 and 32 may be em-

ployed as the intake, the remaining nipple being the discharge, depending upon the direction of rotation of the rotor 17.

Operation

- 5 Let us assume that the rotor 17 is turning clockwise, in which event the nipple 32 would be the intake and the nipple 31 the discharge. The wedge blocks 23 are adjusted so that the 10 sealing bars 22 will closely approach the inner wall of the chamber 10 at the top and bottom sides of the chamber. It is desired to call attention to the fact, however, that the wedge blocks prevent, owing to their dove-tailed construction, the sealing bars 22 from actually touching the walls. They may however be brought to within 1/1000 of an inch of the walls if desired.
- 20 The fluid being pumped flows into the chamber 10 in the rear of each vane. The following vane then, owing to the eccentric position of the wheel tracks 30, closes off the fluid from the intake and forces it toward the outlet 31 as is usual in rotary pumps. At no time, however, 25 is there frictional contact between the vanes and the pump wall to cause wearing away of the vanes and wall.
- 30 Immediately below each nipple 31 and 32, a chamber wall is inclined outwardly as shown at 35 so as not to restrict the intake or discharge passages. It will be noted that, at the positions 35, the vanes are widely separated from the walls, owing to the circular contour of the track grooves 30, and the non-circular contour 35 of the pump chamber wall. This allows a wide unrestricted channel for the inflow and outflow of the fluid from the bottom or operating portion of the chamber. These wide unrestricted 40 passages are unusual in rotary pumps.
- 40 Naturally, as the rotor rotates, centrifugal force will tend to expand or throw the vanes outwardly. This outward force is completely absorbed by the wheels 29 through the roller bearings 20 so that it does not cause frictional 45 rubbing contacts. Side friction is also eliminated on the vanes by the rollers 20 so that the pump operates practically without sliding frictional contacts. It will be noted that should there be any leakage through the packing glands 13, it cannot reach the bearings 15 as 50 it will be thrown from the shaft in the open space between the packing glands and the bearings.
- 55 A small flange 36 may be formed on the peripheral edges of the faces of the rotor 17. Each of the flanges 36 fits snugly into a circular groove 37 in each face plate 11. The flange tends to prevent leakage past the faces of the rotor 17.
- 60 While a specific form of the improvement has been described and illustrated herein, it is desired to be understood that the same may be varied, within the scope of the appended claims, without departing from the spirit of the 65 invention.
- Having thus described the invention, what is claimed and desired secured by Letters Patent is:
- 70 1. A rotary pump comprising: a cylindrical housing; a rotor eccentrically mounted within said housing so that its periphery will closely approach one wall thereof; vanes slidably mounted in radial slots in said rotor; means for maintaining said vanes in close proximity to, yet separated from, the wall of said housing during their revolution; a fluid inlet at one side of said rotor; a fluid outlet at the other side thereof; a sealing block slidably mounted in a longitudinal slot in the extremity of each vane; means interposed between the vane and the block to project or withdraw the latter, said means comprising: wedge members between said block and said vane; and means for actuating said wedge members.
2. A rotary pump comprising: a cylindrical housing; a rotor eccentrically mounted within said housing so that its periphery will closely approach one wall thereof; vanes slidably mounted in radial slots in said rotor; means for maintaining said vanes in close proximity to, yet separated from, the wall of said housing during their revolution; a fluid inlet at one side of said rotor; a fluid outlet at the other side thereof; a sealing block slidably mounted in a longitudinal slot in the extremity of each vane; and means interposed between the vane and the block to project or withdraw the latter, said means comprising: inclined surfaces on said block provided with dove-tailed grooves, there being a dove-tailed groove in said vane opposite said first groove; and dovetailed wedge blocks co-acting with said grooves to project or withdraw said sealing block as desired.
3. A rotary pump comprising: a cylindrical housing; a rotor eccentrically mounted within said housing; vanes slidably mounted in laterally extending radial guideways in said rotor; each of said vanes having a slot extending longitudinally along its outer end; a sealing block slidably mounted in each slot so as to extend beyond said vane, the bottom of each sealing block having an inclined surface; a wedge block positioned between the bottom of said slot and said inclined surfaces; means for moving said wedge block so as to force said sealing block outwardly or draw it inwardly so as to increase or decrease the length of said vanes as desired; said means including dove-tailed connections between said inclined surface and said wedge block and between the bottom of said slot and said wedge block so that the latter may exert a pulling as well as a pushing action.
4. A rotary pump comprising: a cylindrical housing; a rotor eccentrically mounted within said housing; vanes slidably mounted in laterally extending radial guideways in said rotor; each of said vanes having a slot extending longitudinally along its outer end; a sealing block slidably mounted in each slot so as to extend beyond said vane, the bottom of each sealing block having two opposed inclined surfaces on its bottom; a dove-tailed spline extending along the bottom of said slot; a wedge block in each extremity of said slot in interlocking engagement with said splines; and a threaded rod passing through both said wedge blocks so as to actuate them toward or away from each other.

CHARLES SMITH.
